BILLFOLD

Jac B. Anderson, West Bend, and John Hughes, Jr., Milwaukee, Wis., assignors to Enger-Kress Company, West Bend, Wis., a corporation of Wisconsin

Application May 26, 1955, Serial No. 36,216

Term of patent 14 years

(Cl. D87—3)

Fig. 1.

Fig. 2.

Fig. 3.

Fig. 1 is a plan view of a billfold showing our new design, the reverse side being substantially plain;

Fig. 2 is an edge view of the billfold of Fig. 1; and

Fig. 3 is an end view looking at the left hand edge of Fig. 1.

We claim:

The ornamental design for a billfold, substantially as shown.
